JULIUS E. MERRIMAN, OF WEST MERIDEN, CONNECTICUT, ASSIGNOR TO FOSTER, MERRIAM & COMPANY, OF SAME PLACE.

Design No. 4,638, dated February 7, 1871.

DESIGN FOR A DRAWER-PULL.

The Schedule referred to in these Letters Patent and making part of the same.

To all whom it may concern:

Be it known that I, JULIUS E. MERRIMAN, of West Meriden, in the county of New Haven and State of Connecticut, have invented a new Design for Drawer-Pull; and I do hereby declare the following when taken in connection with the accompanying drawing and the letters of reference marked thereon, to be a full, clear, and exact description of the same, and which said drawing constitutes part of this specification, and represents in—

Figure 1, a side view;

Figure 2, an end view; and in

Figure 3, a longitudinal section.

This invention relates to a design for that class of drawer-pulls in which the knob is pivoted to the socket fixed to the front of the drawer, so that, when the knob is not required for use, it will hang down in a perpendicular position; and

The design consists in the peculiar form of the jointed portion of the knob, as fully shown in the accompanying illustrations, and as hereafter described.

A is the knob, constructed or provided with a ball,

B, upon its end, with a neck, a, between the knob and ball.

C is a socket formed upon a base, D, which is provided with a bolt, E, or otherwise constructed for securing to the drawer.

The socket C is of ball-shape, hollow, and open to receive the ball B of the knob, as seen in fig. 3, into which the ball is placed and secured by a pivot or otherwise, so that the knob may be raised into the position denoted in broken lines, fig. 1.

Upon the under side the socket is cut away only so much as to permit the knob to fall perpendicularly, making a stop, d, to prevent the knob, when dropped, from striking the front of the drawer.

I claim as my invention—

The design for drawer-pull herein described, consisting of the peculiar-shaped connection between the head and socket, as shown in the accompanying drawing.

Witnesses: JULIUS E. MERRIMAN.

A. J. TIBBITS,

J. H. SHUMWAY.
